1 Claim

ABSTRACT OF THE DISCLOSURE

This disclosure relates to a shoe tree having a forward member and a rearward member swingably connected thereto and means adapted upon actuation to approach towards and space from each other said forward and rearward parts of the shoe tree.

BACKGROUND OF THE INVENTION

The present invention relates to a shoe tree having an anatomic shape and of the type with interarticulated parts. 20

It is known that commercially available shoe trees of said type adopt the use of devices which simultaneously connect the component parts of the shoe tree and enable the mutual spacing apart or approachment of said parts. These devices are generally formed by a plurality of articulated levers having an essentially "pantograph" movement, as well as means designed to control the movement of said levers.

Whilst these devices are widely employed in anatomic shoe trees and whilst they are advantageous from some points of view, they are nevertheless subject to not inconsiderable disadvantages among which the most notable is the laboriousness and difficulty of manufacture of the devices.

Another disadvantage manifests itself in the corresponding difficulty and laboriousness inherent in the operation of mounting said devices on shoe trees. A further disadvantage is due to the fact that said devices are generally of unwieldy dimensions whence their application to anatomic shoe trees is such as to alter the "line" of the shoe tree.

SUMMARY OF THE INVENTION

The main object of the present invention is that of devising an anatomic form shoe tree of articulated type which employs a device for the connection of the component parts and for the mutual spacing apart and approachment of said parts, said device being such as to obviate completely the above-indicated disadvantages; that is to say a device of ready and economic manufacture and similarly ready and rapid fitting to shoe trees, as well as having limited encumbrance dimensions in order to be well adapted to the "line" of the shoe tree.

Another object of this invention is that said device be of general application and of simple working even after a prolonged period of non-use.

A not final object of the present invention is that said device be easily obtainable from materials which are of ready commercial availability and such as to provide the normally required qualities of high mechanical resistance and resistance to wear, as well as involving known work processes designed to enable high daily productions in manner such that the shoe tree according to the invention be advantageous also from a strictly economic point of view.

These and still other objects, which will better appear hereinafter, are achieved by a shoe tree having a forward member with surfaces having a shape corresponding substantially to the shape of the interior surfaces of at least one forward part of a shoe and a rearward portion with surfaces corresponding substantially to the shape of the

2

interior surfaces of at least a rearward part of the shoe, characterized in comprising a rod arranged between said forward and said rearward parts and extending in the longitudinal direction of the shoe tree, said rod having sections with opposite screw threads and a control member for rotating it, threaded holes in said forward and said rearward parts, said sections with opposite screw threads being respectively adapted to be screwed in said threaded holes, thereby to approach towards and space from each other said forward and rearward parts of the screw thread.

BRIEF DESCRIPTION OF THE DRAWING

Further characteristics and advantages will appear more clearly from the following detailed description of an anatomic shoe tree according to the invention, illustrated by way of non-limiting example in the accompanying drawing in which:

FIG. 1 shows a perspective view of a shoe tree according to the invention;

FIG. 2 shows a perspective and partly separated view of a device for the connection, spacing apart and approachment of the component parts of said shoe tree according to the invention;

FIG. 3 shows a longitudinal median section of said device associated to said parts in closed position;

FIG. 4 shows a longitudinal median view of said device associated to said parts in open position.

DESCRIPTION OF THE PREFERRED EMBODIMENT

With reference to the said figures, the shoe tree 1, according to the invention, which is advantageously produced in synthetic plastics material, has an anatomic form and is constituted by parts 2 and 3 associated to one another in essentially articulate manner by a connection device generally indicated at 4 in FIG. 1; this device 4, which will be described in greater detail hereinafter, enables the mutual spacing and approachment of said parts 2 and 3. Said part 2 is provided, at the end thereof facing the part 3, with a pair of transverse baffles 5 and 5a defining an externally accessible space 6 therebetween in which a plate-like member 7 is arranged in essentially snap engagement manner, whereby member 7 is fixed in its position.

In order to prevent member 7 to be extracted from its exact position between the baffles 5, 5a, a stop or catch 7a may be provided on the bottom of member 7 cooperating with the flange-like portions 7b on the top of member 7 thereby engaging therebetween the baffle 5.

The mounting may be achieved by elastic deformation of the synthetic material of which the entire device is preferably made.

The part 2 is provided with substantially plate-like bottom member 8 arranged adjacent the insole of the shoe tree and provided in its upper section with longitudinal reliefs or guideways 9 and 10. Bottom member 8 is advantageously molded as an integral member of the side wall 2a of the part 2 and of the baffle or cross-piece 5a. Also the baffle or cross-piece 5 is molded as an integral member of part 2 so that the parts 2, 5, 5a and 8 may be molded as one piece. The bottom member 8 may be arranged at a distance from side wall 2b of part 2 so that a gap is provided therebetween which allows a better handling and mounting operation. Shoulders 2c and 2d are provided as suitable stop means.

The part 3 is transversely provided with spaced baffles 11, 11a, which define a space 12 therebetween in which a plate-like member 13 is arranged in essentially snap engagement manner.

To prevent extraction of member 13 from its position between baffles 11 and 11a a catch or stop portion 13a is provided on the bottom of member 13 and engaging

the bottom of baffle 11. A flange portion 13b engages the top of baffle 11, thus preventing any vertical movement of member 13.

This plate-like member 13 is hinged through its upper flange-like portion 13b and, by pivoting along an axis 14, to a further plate-like member 15 which is provided in its lower section with notches 15a and 16 arranged to be slidingly engaged with said reliefs or guideways 9 and 19. The hinge connection between members 13 and 15 is obtained by pin-like projections coaxial with axis 14 provided rigid with member 15 and engaging rotatably in holes provided in lugs extending from the sides of the flange like portion 13b. Consequently, in assembled position member 13 is rigid with member 3 and may be rotated together therewith about the axis 14. The device for the connection and the mutual spacing and approachment of the parts 2 and 3 comprises further a rod 17 having two inversely threaded sections 18 and 19. These sections 18 and 19 are respectively screwed in threaded holes 17c and 15b provided in the plate-like member 7 and the plate-like member 15 respectively under the control of a knurled knob 20 mounted in central position on said rod 17 and fast therewith.

The mounting and the working of the previously described device will be evident. In fact, by effecting a simple rotation of the knob 18, the mutual spacing or approachment of the plate-like members 7 and 15 is determined and thus of the parts 2 and 3 connected therewith and forming the anatomic shoe tree according to the invention.

The movement of said parts is further eased and centered by the presence of said longitudinal guides 9 and 10 in constant engagement with the notches 15a and 16 of the plate-like member 15.

From what has been described and illustrated it will be evident that the shoe tree according to the invention achieves completely all the pre-determined objects, with especial reference to the simplicity of its structure the ease of manufacture and the general and practical application of the device employed by it for the articulation of the component parts. Moreover, the limited encum-

brance presented by this device is such as not even minimally to alter the aesthetic "line" of the shoe tree according to the invention.

I claim:

1. A shoe tree having a forward member with surfaces having a shape corresponding substantially to the shape of the interior surfaces of at least one forward part of a shoe and a rearward portion with surfaces corresponding substantially to the shape of the interior surfaces of at least a rearward part of the shoe, a rod arranged between said forward and said rearward parts and extending in the longitudinal direction of the shoe tree, said rod having sections with opposite screw threads and a control member for rotating it, a plate member having a threaded hole, said plate member and one among said rear and said forward parts having hinge means to hingedly connect together said plate-member with said one part about an axis transverse to said rod, another plate-member fixed on the other among said rear and said forward parts and having a threaded hole, said sections with opposite screw threads being respectively adapted to be screwed in said threaded holes, thereby to approach towards and space from each other said forward and rearward parts of the shoe tree, and wherein according to the improvement said rear and forward parts have spaced plate-like baffle members defining an interspace therebetween and wherein said plate-like members are inserted in said interspaces thereby to be clamped therebetween, said plate-like members having flange-like portions engaged with the edges of said baffle members.
